FLUID COKING RESIDUAL OIL

John F. Moser, Jr., and Frank B. Johnson, Baton Rouge, La., assignors to ESSO Research and Engineering Company, a corporation of Delaware

Application October 7, 1953, Serial No. 384,554

2 Claims. (Cl. 208—127)

This invention relates to the coking of residual oils and pertains more particularly to the coking of such oils in the presence of hot fluidized solids.

It has previously been proposed to coke high boiling residual oils in the presence of finely divided solids maintained at a temperature sufficient to convert the oil into vapors and coke. According to one mode of operation, the stream of the solids is withdrawn from the coking vessel and cycled through an external heater in which sufficient heat is imparted to the solids to supply the necessary heat for the operation.

One of the limitations to the fluid type coking process is that the amount of oil which can be charged to the coking vessel per unit time for a given weight of solids in the reactor must be carefully controlled.

For economic reasons, it is desirable to operate the coking vessel of given size at a maximum permissible feed rate. However, if the feed rate is too high, the solid particles in the bed lose their fluid characteristics due to the presence of unvaporized tarry matter present in the feed. This has become known as "bed bogging." The bogging of the bed is a particularly serious matter because when it happens, it is necessary to quickly interrupt the coking operation and to remove the solidified bed from the coking vessel. The latter is a laborious and time-consuming operation.

It is, therefore, important to be able to quickly detect potential bed bogging conditions so that appropriate action may be taken to avoid such disastrous consequences.

The main object of the present invention is to provide a simple and effective method of detecting potential bed bogging conditions.

It has been found that for a given set of coking conditions, such as coking temperature, solids residence time in the coking vessel, etc., the maximum permissible feed rate of oil which will avoid bogging the bed will depend upon the Conradson carbon content of the feed. The Conradson carbon content is a standard test for residuum oils described in numerous petroleum hand books, such as "The Science of Petroleum," vol. 2, pp. 14-17 and 14-18. Briefly, it is the weight percent of solid residue remaining after heating a standard sample under standard test conditions. It has been found that in a typical fluid coking operation in a test unit at a temperature of 1000° F., for example, the maximum permissible feed rate for 100% conversion which will avoid bogging of the bed is about 0.74 part by weight of feed per hour per part of weight of solids in the coking vessel when the feed has a Conradson carbon value of 18. When the feed has a Conradson carbon value of 23, the feed rate is about 0.58 and with a Conradson carbon value of 28, the feed rate is about 0.48.

For a given set of coking conditions, therefore, the feed rate can be controlled to avoid bed bogging by determining the Conradson carbon value of the feed. However, Conradson carbon determinations consume about one-half hour and, therefore, cannot be used to quickly de-

2

tect rapid changes in the feed which may result from fluctuations in the crude distillation equipment from which the feed is derived.

It has been found that for a feed derived from any given crude source, there is a direct relationship between its viscosity and its Conradson carbon content. For example, a South Louisiana residuum having a Conradson carbon content of 18 will have a viscosity of about 70 S.S.F. (Saybolt seconds Furol) at 275° F., heavier residuum derived from the same source having a Conradson carbon content of 23 will have a viscosity of about 130 S.S.F. at 275° F., and a still heavier residuum derived from the same source having a Conradson carbon content of 28 will have a viscosity of about 250 S.S.F. at 275° F. A residuum derived from Hawkins crude having a Conradson carbon content of 24 will having a viscosity of about 350 S.S.F. at 275° F.

In accordance with the present invention, the relationship between the viscosity and the Conradson carbon value of various samples of the residuum to be coked is first established by simple laboratory methods and the feed rate of the oil to the coking unit expressed as the weight of oil treated per hour per weight of solids in the coking vessel is controlled by frequent or continuous viscosity determinations of the feed.

There are numerous types of continuous viscosity recorders capable of giving accurate and rapid viscosity readings. Frequent or continuous viscosity readings of the feed, therefore, make it possible to quickly detect any sharp changes in the feed quality due to fluctuations in the operating conditions of the crude still and appropriate action can be taken to avoid bogging of the bed. Such corrective action may involve reducing the feed rate, increasing the temperature of the coking vessel or by increasing the amount of solids contained in the coking vessel. The control may be manual or automatic.

Having described the general nature and objects of the invention, reference will now be made to the accompanying drawing in which Figure 1 is a partly schematic and partly diagrammatic illustration of a fluid coking unit capable of utilizing the present invention; and Figure 2 is a curve showing the relationship between the viscosity of feed derived from certain crudes and the Conradson carbon value of such feeds.

Referring to the drawing, the reference character 1 designates the feed line in which the oil to be coked is introduced into the system. The feed for the process is preferably a hydrocarbon residuum such as atmospheric or vacuum bottoms from a crude distillation still, or it may be other types of heavy oils which are generally unsuitable for catalytic cracking, such as a heavy initial condensate from a catalytic cracking unit, commonly known as clarified oil.

The oil introduced through feed line 1 may be preheated to any desired temperature below active coking temperature for the oil. For example, the oil may be preheated to a temperature of from 500-700° F. The feed passing through line 1 is discharged into the reaction vessel 2 preferably through a manifold line 3 having a plurality of branch lines 4, 5, and 6, which discharges the oil into the reaction vessel at various levels.

The coking vessel 2 contains a fluidized bed of hot finely divided solids having an upper level which is generally indicated at 7. This level is not quiescent but is highly turbulent similar to a violent boiling liquid. The solids in the reactor are maintained in a dense turbulent fluidized condition by gases and vapors rising upwardly therethrough.

The invention will be described using petroleum coke as the circulating solids. The coke particles should be of a size range capable of maintaining good fluidity. For example, the average size of the individual particles in

typical operation may range from 125 microns to 500 microns. It will be understood the particles grow during the process as a result of coke formed so that it is necessary to replace coarser coke with finer to maintain the desired size range. Some of the coke withdrawn may be ground and returned or grinding may be carried out in the operation. The density of the bed of fluidized solids in the coking vessel may range from 35 to 60 pounds per cubic foot. To obtain the desired turbulence in the bed, the minimum superficial velocity of the rising gases and vapors should be between .5 and 3 feet per second and may be higher depending on the average particle size of the coke and other factors.

The superficial velocity is the velocity the gases and vapors would travel in the absence of solids in the coking vessel. These gases and vapors will comprise all the gas introduced for stripping as later described and the vapors formed during the coking reaction.

The temperature maintained in the coking vessel 2 may be between 900 and 1200° F. and sufficient to crack the heavy oils into vapors and coke.

The intermediate section 8 of the reactor 2 above the lower feed injection line 6 may be tapered as indicated so that the velocity of the gases rising through the bed will be maintained more or less uniform throughout its depth despite the formation of additional gas and vapors in the upper section. The bottom section 9 of the reactor serves as a stripping well for removing vaporized products from the solids prior to circulating the solids to the burner vessel as hereinafter described. Stripping gas, such as steam, is introduced into the bottom of the stripping section through line 10 and branch lines 11, 12, and 13. A conduit 14 projects upwardly into the stripping section 9 for removing excess coke formed by the process. Any large agglomerates which formed in the process will be collected at the extreme bottom of the stripper section 9 and may be withdrawn therefrom through line 15.

A separate stream of coke particles is withdrawn from the stripping zone 9 and passed through a transfer line 16 to the heater 17.

This transfer line is constructed and operated in a manner described in U.S. Patent 2,589,124, filed May 1, 1950, and issued March 11, 1952. The transfer line is provided with a U-shaped conduit at the base which forms a seal for preventing passage of gases from the coking vessel to the heating vessel, or vice versa. The depth of the U-seal below the point of injection of the air to the heater is sufficient to develop a pressure greater than the normal fluctuations of the air pressure.

The solids, during their passage through the transfer line 16, are maintained in a fluidized condition. For example, aerating taps 18 may be provided at spaced points along the base of the U-bend to maintain the solids in a dense fluidized state. The amount of gas so introduced is usually controlled to maintain the solids in a dense fluid state.

The transfer line 16 is provided with a riser section 19 which has its upper open end located within the heater vessel. Air is added to the riser through line 20. Additional air is introduced into the bottom of the heater 17 through line 21. The total amount of air added is controlled to burn enough coke to furnish the required heat for the process as before described. The amount of air added to the riser pipe 19 is regulated to control the flow of solids between the heater and the coking vessel. The remaining air necessary is added to the bottom of the vessel 17.

As illustrated, the heater 17 contains a dense fluidized body of finely divided solids undergoing heating in the bottom section. Air is introduced into the bottom section of the heater and passes upwardly through the bed at a velocity sufficient to maintain the particles in a dense fluidized state. The invention, however, is not restricted to any particular type of heater since any type of furnace could be used.

The heated particles overflow from heater 17 through an outlet line 22 which has an open end projecting up into the heater. The hot solids withdrawn from the heater 17 through outlet line 22 are transferred through a transfer line 23 and are reinjected into the reaction vessel 2 at an intermediate point in the coking vessel as illustrated. This transfer line is similar in construction to transfer line 15 and operates in a manner similar to U.S. Patent 2,589,124 previously mentioned. The hot solids from the heater 17 automatically overflow into the outlet conduit 22 so that a constant level of fluidized particles are maintained in the heater 17.

Hot combustion products from the heater discharge into a cyclone 24 which serves to remove particles entrained in the combustion gases. The hot combustion products after passing through the cyclone 24 are removed through line 25. These gases may be subjected to further separation, such as by the use of additional cyclones, for final separation of the entrained powder. Solids separated from the gases in the cyclone 24 are returned to the dense bed through a dip pipe 26 which terminates below the level of the bed to provide an effective seal and prevent gases from blowing up through the dip pipe.

Vaporized hydrocarbons formed in the coking vessel 2 are passed to a cyclone separator 27 located in the top of the vessel. Solids removed from the vapors in the cyclone are returned to the coking vessel through the dip pipe 28. The vaporized hydrocarbons are withdrawn from the vessel through line 29 and subjected to further separation and purification as desired.

In carrying out the present invention, a continuous sample of feed from line 1 is passed through continuous viscosity indicator, recorder, or recorder-controller 30 maintained at constant temperature and the indicated viscosity is used as a control to avoid potential bed bogging. Before starting the coking process, it is first necessary to make preliminary tests to establish the relationship between the viscosity and the Conradson carbon value of the feed. The Conradson carbon value will determine the maximum permissible feed rate which will avoid bed bogging under the obtaining temperature conditions.

For illustrative purposes, the relationship between the viscosity of the residua derived from South Louisiana and Billings crudes and the Conradson carbon value is shown in the chart forming Figure 2 of the drawings. This figure shows the relationship between the viscosity and the Conradson carbon value of the residuum. It cannot be concluded that all residua regardless of source have the same relationship as shown on the curve. However, this relationship can be readily determined by simple Conradson carbon and viscosity determinations. Having determined this relationship and knowing the maximum feed rate permissible for a feed having the Conradson carbon value so determined at the obtaining temperature conditions, the coking process can be readily controlled to operate within safe limits which will avoid bed bogging. If the viscosity of the feed should change to such an extent that potential bed bogging conditions exist, remedial steps such as decrease in feed rate, or increase in temperature may be taken. All of these steps effect the severity of the coking operation.

What is claimed is:

1. In a process of operating a fluid coking unit in which a stream of residual oil is introduced into a fluidized mass of sub-divided solids maintained at a coking temperature in the range of 900° to 1200° F. and wherein the solids are maintained in a dense turbulent fluidized bed in the coking zone by gases rising upwardly therethrough; the improved method of preventing loss of fluidity of the bed which comprises determining the maximum permissible feed rate based on the Conradson carbon of the feed, determining the relationship between the viscosity and Conradson carbon of the feed, con-

tinuously determining the viscosity of the feed passing into the coking zone and varying directly the severity of the coking operation with the viscosity of the oil when the viscosity of the feed changes a predetermined amount, the maximum feed rate employed being 0.74 part by weight of feed/part by weight solids/hour.

2. In a process defined in claim 1, the further improvement which comprises reducing the feed rate to the coking zone when the viscosity of the feed increases a predetermined amount.
